Primary Examiner — Robin V Webster**CLAIM**

(57) The ornamental design for a drop filter, as shown and described.

DESCRIPTION

FIG. 1 is a perspective view of the drop filter according to an embodiment of the present invention;

FIG. 2 is a front view of the drop filter shown in FIG. 1;

FIG. 3 is a back view of the drop filter shown in FIG. 1;

FIG. 4 is a right side view of the drop filter shown in FIG. 1;

FIG. 5 is a left side view of the drop filter shown in FIG. 1;

FIG. 6 is a top view of the drop filter shown in FIG. 1; and,

FIG. 7 is a bottom view of the drop filter shown in FIG. 1.

The broken lines in the Figures show the environment of the claimed drop filter. The broken lines in all of the Figures form no part of the claimed design.
